UNITED STATES PATENT OFFICE.

GEORGE E. GOODING AND EUGENE H. TAYLOR, OF LYNN, MASSACHUSETTS.

EDGE-TRIMMING TOOL.

SPECIFICATION forming part of Letters Patent No. 228,456, dated June 8, 1880.

Application filed March 24, 1880. (No model.)

To all whom it may concern:

Be it known that we, GEORGE E. GOODING and EUGENE H. TAYLOR, both of Lynn, in the county of Essex and State of Massachusetts, have invented an Improved Edge-Trimming Tool, of which the following description, in connection with the accompanying drawings, is a specification.

This invention relates to improvements in a tool for edge-trimming the soles and edges of boots and shoes, and has for its object the production of a tool having interchangeable parts, which, if broken or worn out, may be readily renewed.

Our edge-trimming tool is of that class in which the system of guides and gages is clasped upon the blade of a shoe-knife of ordinary or suitable construction.

In this our invention we employ a block having attached to it a clip by which to adjustably secure the block and its attached parts upon the knife-blade. This block has adjustably connected with it a vertically, horizontally, and laterally adjustable edge-gage. The guard to run in the rand-crease, or between the rand and upper, is made as a separate piece from the block. Separating the edge-trimming tool in this way into independent parts secures economy in the cost of tools.

Figure 1 represents one of our edge-trimming tools shown as applied to a shoe-knife blade, the blade and parts of the tool being shown in working position with relation to the edge of a shoe-sole; Fig. 2, a right-hand-side elevation of the tool shown in Fig. 1, the blade of the knife being omitted. Fig. 3 shows the guard separated from the block; Fig. 4, an end view looking upward from Fig. 1, the blade being omitted; Fig. 5, a top view of Fig. 2; Figs. 6 and 7, inner-side and outer-side views of a modification to be referred to, and Fig. 8 an end view of the guard used in Figs. 6 and 7.

The block *a* has attached to it, by the screw *b*, the clamping-plate *c*, preferably made of spring metal, so as to clamp the blade *d* of any usual shoe-knife between itself and the block in the space *e*. But one screw is herein needed for this purpose, as the front end of the clamp is fitted into a recess in the block *a* behind a stud or clamp-holder, 2, (see Fig. 2), forming part of the block *a*.

The guard *f*, which is to run in between the rand *g* and shoe-upper *h*, is of usual shape; but, instead of forming part of the block *a*, its shank *f'* is provided with a screw-hole, 3, and a shoulder, 4, the former to receive a screw, 5, and the latter to enter a proper groove made for its reception in the said block *a*, thus permitting the guard to be renewed. One block *a* will outlast a number of guards.

The block *a* is suitably grooved (see Fig. 4) to receive the shank *i* of the gaging devices. As herein shown, one edge of the said shank *i* is confined by the separable flanged plate *k* and the two screws *l*. The shank *i*, when in adjusted position, is held against longitudinal movement by the screw *6*. The shank *i* has at its lower end a dovetailed or other equivalent shaped guide-head, *m*, which enters a dovetailed groove in a slide, *n*, which, at its opposite side, has a second dovetailed or equivalent shaped groove at right angles to the length of the block (see Fig. 2) to receive the horizontally-adjustable plate *o*, that at its outer end has a stud, 8, upon which is placed the edge-gage *p*, herein shown as a roller.

The plate *o* has an elongated slot, 10, to receive the set-screw 12.

Adjusting the plate on the slide *n* controls the thickness of the chip taken from the sole-edge. Adjusting the block longitudinally on the part *m* enables the roller-gage to bear upon the material to be trimmed in the proper position with relation to the cutting-edge of the knife-blade to insure a smooth cut, this adjustment providing for change of position as the knife, in grinding, is worn away.

The adjustment provided for by set-screw 6 enables the gage to be run along the edge of the sole as near the welt as possible, but preferably not upon the welt, for the sole-edge cut out by a die is smoother and more regular than the edge of the welt.

Instead of supporting the roller-gage as hereinbefore described, we may extend the guard *f* upward, as in Figs. 6 and 8, slot it at 13 to receive a screw, 14, by which to adjustably secure to the said guard the plate *r*, which, in function and purpose, is the equivalent of the plate *o*, hereinbefore described. This plate *r* has a stud, upon which is held the roller edge-gage *p*.

We claim—

1. In an edge-trimming tool, the block provided with the projection 2, combined with the clamp *c* and the screw *b*, substantially as described.
2. The guard to run in the rand-crease, and provided with a screw-hole and notched part 4, combined with the block *a*, grooved to receive the part 4, and the screw 5, by which to attach the shank *f'* to the block, as described.
3. The block *a* and its attached guard, combined with the edge-gage *p*, made adjustable toward and from the outer edge of the said guard to regulate the thickness of the chip or piece to be trimmed from the sole-edge, substantially as described.
4. The block *a* and guard, combined with the edge-gage, supported substantially as described, and made adjustable in the direction of the length of the gage *f* to adapt the gage

to the edge of the knife-blade whatever may be its width.

5. The grooved block *a* and clamp and guard, combined with the shank *i*, adjustable on the block, and the grooved slide *n*, plate, and edge-gage, to operate substantially as described. 25

6. In an edge-trimming tool, the block and clasp to hold a knife-blade, combined with the guard *f*, to move in the rand-crease, and the wheel-like edge-gage *p*, substantially as described. 30

In testimony whereof we have signed our names to this specification in the presence of two subscribing witnesses.

GEO. E. GOODING.
EUGENE H. TAYLOR.
